APPARATUS FOR THE TRANSMISSION OF
ALARM SIGNALSLouis Chauveau, Paris, France, assignor to Societe
Française Radio-Electrique, a corporation of
FranceOriginal application January 13, 1948, Serial No.
1,976, now Patent No. 2,533,765, dated Decem-
ber 12, 1950. Divided and this application Au-
gust 2, 1950, Serial No. 177,267. In France Jan-
uary 29, 1947

2 Claims. (Cl. 340—345)

1

The purpose served by alarm-selecting apparatus installed in ships is to release an acoustic warning device when the regular alarm signal is received by the radiotelegraphic receiver of the ship. This regular signal is composed of a series of twelve dashes of four seconds duration separated by intervals of one second. The selector must respond to three or four consecutive dashes.

This regular signal is keyed manually, so as to be sent out, by the operator of the ship in distress. Generally, this operator uses as a guide or check a clock or watch with a second-hand for checking his keying. As a result, the dashes and spaces actually transmitted are not so accurate as they should be.

To allow for this inaccuracy, the limits of a correct dash had been tolerated to be 3-5 seconds, whereas spacing could attain 5 seconds time. Thus, there is a large probability of reception 20 of a signal formed by hand more or less correctly.

Recent regulations have made the above limits narrower and at the present time the correct dash must be comprised between 3.5 and 4.5 seconds duration and spacing must not be over 1.5 seconds. Because of this accuracy, the modern auto-alarm selectors require as a consequence, more accurate keying by the operator. If one considers the circumstances of distress, 25 it is obvious that risks of non-reception of an alarm signal are considerably increased.

The purpose of my present invention is to provide a remedy, to a certain extent, to the aforesaid drawback. It essentially consists in making reversible the auto-alarm apparatus, i. e., in permitting of using them either as reception selec- 30 tors, or automatic transmission keying systems.

This application is a division of my application Serial Number 1,976, filed January 13, 1948 for Selector Apparatus for Alarm Signals, now Patent 2,533,765, dated December 12, 1950.

For indeed, the auto-alarm selectors include all the necessary members for controlling spaces and dashes with accuracy; consequently it will suffice to adapt them in a suitable manner so as to make them control a keying relay which actuates the transmitter of the ship in such manner that the dashes have four seconds duration and spaces one second, the result being readily obtained within a precision of the order 35

of $\frac{1}{10}$ of a second. Under these conditions, in any vessel equipped with an auto-alarm selector provided with the improvement in conformity with the invention, it will be possible, if need be, to transmit the alarm signal with the utmost possible accuracy.

The invention is particularly concerned with the adjunction to existing auto-alarm selectors, of devices permitting of combining the various 10 members of the selector in such manner that the duration of the complete cycle is of 5 seconds and the control of the transmission is interrupted during one second in the course of each cycle; the disposition being such, moreover, that the 15 transmitter thus controlled transmits dashes of four seconds duration separated by spaces of one second. In addition, one may eventually provide a member which stops the system after the transmission of twelve dashes of four seconds.

There is hereinafter given, by way of a non-limitative example, the description of an embodiment of my invention adapted to be applied to an apparatus for the transmission of alarm signals, said apparatus being diagrammatically shown in the accompanying drawings in which

Fig. 1 is a diagrammatic circuit arrangement of the transmitter of my invention; and Fig. 2 is a detail view of the intermittent contactor used in the transmitter.

The auto-alarm selector which is the subject of copending patent application Serial Number 1,976, filed January 13, 1948, for Selector Apparatus for Alarm Signals, now Patent 2,533,765, dated December 12, 1950, substantially comprises a pendular relay or intermittent contactor 1 30 released a short moment after the beginning of the reception of every dash. This relay, shown more particularly in Fig. 2, has a period of the order of one second. It controls by way of its contact 8 the chain of relays shown in Fig. 1 at T₁—AT₁ to T₄—AT₄ in such manner that when the duration of a dash received becomes as great as 3.5 seconds, the contact 28 and T₄ is closed and feeds to the first set of recording relays E₁—AE₁, which keeps being energized so long as the alarm signal received is correct.

At the time of the second dash, the recording is effected on relays E₂—AE₂. At the time of the third dash, relays E₃—AE₃ operate and the alarm warning devices SON are set into action.

When a dash lasts for 4.5 seconds, thus being

incorrect, a relay T_5 is energized by the fifth pendular impulse; then this relay T_5 through contact 34 cuts off the general power supply of the system, setting the whole apparatus to standstill.

When relay AT_4 works, that is when a correct dash has just been received, the contact 32 supplies a system SIL of slugged relay with capacitor 33 and resistor 34, the whole having a time constant of 1.5 seconds; as a result, at the end of a correct dash, SIL maintains the whole being supplied so long as silence does not last more than 1.5 seconds.

The starting-up of the above system is promoted at the beginning of each dash by the slugged relay DM, itself controlled by the reception relay RR.

I provide in the circuit a switch I, a starter relay CEM, and a relay RM, which keys the transmitter when it is energized. The relay E_1 must be fitted with an extra back contact A and relay T_5 must be fitted with an extra make contact B. The additional elements are connected to the preselector comprising the invention as shown in the broken line wiring diagram of the drawing.

As can be seen, the switch I closes the circuit of the relay CEM. The latter carries a change-over contact C which transfers the circuit of DM from contact 7 of RR to make it connect by way of contact B of T_5 ; this relay CEM is also fitted with a make contact D which short circuits part of the resistance 34. As a result of this short circuiting, the time constant of the assembly, relay SIL, condenser 33 and resistance 34, is reduced from 1.5-0.5 seconds. The operation of the apparatus is now as follows:

Supposing that at the instant of closing switch I the relay RR is unenergized, the relays RM and CEM will operate; the latter by its contact C tends to supply DM; but the contact B of T_5 being open, DM remains at rest. The voltage divider 2 is therefore supplied with power, the intermittent contactor 1 operates, transmits an impulse 0.1 second after receiving its starting torque, and the network relays T_1-AT_1 to T_4-AT_4 close step by step.

On the fourth impulse of the intermittent contactor, that is to say a time period of $3+0.1=3.1$ seconds after the closing of switch I, relay E_1 operates and the contact of relay RM opens. At the same time the shunt network, SIL condenser 33 and resistance 34, charges up.

At the fifth impulse, relay T_5 operates, cuts the general supply (voltage divider 2) and locks on by way of the contact of relay SIL.

The relay T_5 by its contact B provides for the energizing of DM which opens its contact 5. The energizing of relay T_5 is assured by the contact of SIL for a period of 0.5 second, after which, relay SIL and relay T_5 are energized. 0.4 second after the deenergizing of relay SIL, DM drops off, the voltage divider is again energized, and the whole cycle of operations described above is repeated. This condition persists as long as the switch I is closed.

The synchronously oscillating relay or intermittent contactor 1, shown in Fig. 2, is constituted in the following manner: A flywheel 9 mounted on a shaft 10 to which is attached the spiral spring 11 constitutes a balance wheel whose period is of the order of 1 second; that is to say it makes two half oscillations per second. The shaft is supported in two bearings 12 and 13. In order to promote starting up and to ensure the oscillation of the balance wheel, this wheel car-

ries a magnetic portion 14, which is attracted by the solenoid 15, the circuit of the latter being controlled by the contact 16, the latter contact working under the action of an arm 17 integral with the shaft. The whole is contrived in such a way that contact 16 is not closed by arm 17 other than when the balance wheel is displaced in a clockwise direction, contact 16 being open when a movement takes place in the other direction. 10 The wheel carries another arm 18 which controls contact 18 under the same conditions.

The shaft 10 carries a flanged collar 19 with a rounded notch which engages the roller 20 carried by lever 21 which rotates about a shaft 15 25. A spring 22 pulls in this lever so that it maintains the balance wheel in its position of rest. The lever 21 can be displaced by the solenoid 23 so that it frees the balance wheel and allows it to go into action.

To obtain a good performance from such an intermittent contactor it is essential that the magnetic portion 14, the solenoid 15 and the contact 16, are in well defined positions in relation with each other.

25 They must not therefore be displaced from these positions. On the other hand contact 8 can be displaced in a slot 24. It is therefore possible to obtain an advance or retard in relation to the balance movement by the positioning of 30 the contact which ensures very precise adjustment of the measure of duration of a dash, as will be explained by the following:

This positioning of the moving contact 8 constitutes another feature of the invention.

35 Normally, in balance wheel devices of this kind, the whole is adjusted so that, when at repose, that is to say at the engagement of roller 20, the arm 17 is a little behind contact 16; the spiral spring 11 is then lightly wound up in such a way that when unlocking takes place, the arm 17 under the influence of the spiral spring makes contact 16, whence an impulse of current travels to the solenoid 15, and the system starts operating. However, this method of starting-up is 40 precarious, the useful torque of the balance wheel being very small at the moment of starting-up.

Another feature of the invention lies in the association of a balance wheel with a torque relay LAN, these two elements being interconnected according to Fig. 1.

50 The relay LAN is disposed in such a way as to impart a strong current impulse to the solenoid 15 at the moment of unlocking, and up to the time of the establishment of contact 16; at this 55 moment the relay LAN operates so as to include the contact 16 in the circuit of the maintaining solenoid 15. A resistance 25 allows control over the intensity of the impulses to obtain correct and continuous functioning of the oscillating relay. 60 At the moment of the transmission of a dash, circuit A is switched on with a lag 0.4 second, the unlocking relay 23 operates freeing the balance wheel of the oscillating relay; at the same time the maintaining solenoid 15 is fed by 65 way of contact 26 of relay LAN which is not yet energized. A strong impulse drags the balance wheel in a clockwise direction until arm 17 closes contact 16; this latter then feeds relay LAN which closes and locks on by its contact 27. Contact 26 connects the solenoid circuit 15 to the resistance 25 and contact 16.

70 It is thus evident that the balance wheel receives a first and strong impulse, which ensures prompt starting-up and that it maintains its

oscillation under the action of suitably regulated impulses transmitted by contact 16.

At each oscillation contact 8 is closed. At the first oscillation its closing takes place about 0.1 second after the commencement of oscillation of the balance wheel. It controls the circuit of the relay network T₁—T₄ together with that of the auxiliaries AT₁—AT₄ in such a way that one set of relays is energized at each impulse.

In light of the foregoing, each cycle of the alarm transmitter can be split up into four periods: one period of 0.1 second, corresponding to the delay in the transmission of the first impulse by the intermittent contactor; one period of 4 seconds corresponding to four complete oscillations of the intermittent contactor, a period of 0.5 second or drop-off-lag of relay SIL, and a period of 0.4 second corresponding to the lag in dropping off of relay DM. This gives a total of 0.1+4+0.5+0.4=5 seconds which represents the working cycle of the transmitter. It must be observed that energizing of relay T₄ effects the energizing relay of relay E₁, while relay T₅ effects the deenergizing of the latter.

As a result during the course of each cycle, the keying relay RM, whose supply is controlled by contact A of relay E₁, will be energized for 4 seconds, and will be at rest for 1 second. Finally, relay RM by way of its contact keys the transmitter.

It can be seen that the apparatus thus constructed ensures the continued transmission of 4 second dashes separated by spaces of 1 second.

Eventually, a twelve contact telephone stepper switch (not shown) may be connected in parallel with RM, or be controlled by the latter, so that after the tenth dash, this stepper breaks the circuit of CEM, thereby terminating transmission.

The auto-alarm selecting apparatus which comprises a stabilized, constant speed motor are equally capable of being improved by using the device of the invention. In the case of such apparatus however, it is simpler to adjoin them to a cam driven by the motor and arranged so as to directly control the appropriate transmission; but it can always be of advantage to adjoin them with the device which is the subject of this invention, so as to permit of stopping the whole system after transmission of twelve dashes.

It will be understood that the examples of application which have been given hereinabove are in no way limiting, and the invention may apply, totally or partly to various types of auto-alarm selectors or any other like apparatus within the scope of the appended claims.

What I claim and desire to secure by Letters Patent of the United States is as follows:

1. In a device for transmitting radio-telegraphic signals composed of a series of dashes of a given duration separated from one another by spaces of another determined duration, a direct current power supply, a potentiometer, three electromagnetic relays each having a contact member, said potentiometer being fed from said power supply through the contact members of said three different relays, a mechanism with pendular oscillations, means for normally blocking said mechanism, means for unblocking said mechanism when the potentiometer is connected to the power supply, means connected to the potentiometer and adapted to impart to said mechanism a constant oscillation period equal to the space duration of said signals and being a submultiple of the dash duration of said signals, a chain of interconnected counting relays, a line

connected to the potentiometer, adjustable means cooperating with said line and with the said mechanism to connect said line to the relays, said means including a member producing one pulse per oscillation period which is actuated by said mechanism during its oscillating movement, a recording relay having a resting contact, means actuated by a make-contact of the last counting relay and adapted to connect the recording relay to the said potentiometer, a relay controlling the transmitter operation, means to connect said last mentioned relay to the power supply through a resting contact of the recording relay, means for periodically opening the circuit to said potentiometer and power supply, said last mentioned means including three relays each having an armature and coacting contacts respectively designated make-and-break cut-off, silence, and starting relays controlling the three aforementioned contacts, and connecting the potentiometer to one terminal of the power supply, the two silence and starting contacts being mounted in parallel, and connected in series with the contacts of the third make-and-break cut-off relays, which separates them from the potentiometer, means associated with the silence relay and with one of the contacts of the last counting relay to actuate the silence make-contact opening with a given time delay, the beginning of the delay period coinciding with the opening of the potentiometer supply circuit, means associated with the starting relay, with a make-contact of the cut-off relay and with the supply circuit of the potentiometer, which are adapted to actuate with a given time delay the closing of the starting contact, this delay period beginning immediately after the opening of the silence contact, means associated with the potentiometer supply circuit and another contact member of the last counting relay, which are adapted to bring the cut-off relay excitation and the beginning of the self-excitation of the silence relay in coincidence with the pulse immediately following the one which caused the last counting relay to be energized, means associated with the make-and-break contact of the cut-off relay and with one of the terminals of the power supply to hold said cut-off relay energized after the displacement of its armature, which effects the opening of said supply circuit, and means for causing the sum of the two said delay times, and of the time interval between the pendular mechanism unblocking and the first control pulse, to equal the oscillation period of said pendular mechanism.

2. A device for transmitting radiotelegraphic signals as set forth in claim 1, in which said mechanism with pendular oscillations includes a dynamically balanced flywheel having a projecting lug thereon made of a non-magnetic metal and having a vertical shaft, unblocking means comprising a cam mounted on said shaft and co-operating with a lever adapted to turn about a vertical axis and controlled by an electromagnet connected to the potentiometer, means for launching said flywheel and maintaining it in isochronic oscillations, said means comprising a circuit including the potentiometer, a fixed magnetic-core coil and a contact cooperating with the projecting lug of said flywheel, said lug being so adjusted as to close the said circuit when the excitation of the unblocking electromagnet takes place, impulse-producing means comprising a lug projecting from the periphery of the flywheel, a circuit connected to the relay chain

holding line through one of the contacts of said relays, a flexible contact closed by the said lug during the flywheel rotation, and adjustable means adapted to adjust the angular position of this lug respectively to the contact in a given position of the flywheel.
